(57) **CLAIM**

I claim the ornamental design for a sole for footwear, as shown and described.

DESCRIPTION

FIG. 1 is a perspective view of a sole for footwear, seen from the front and right side thereof, showing my new design; FIG. 2 is a bottom view thereof;

FIG. 3 is a rear end view thereof; and,

FIG. 4 is a front end view thereof.

The nonstippled surfaces and the surfaces bearing stippling of relatively different densities are indicative of respective differences in contrast and/or color.
